4 Claims. (Cl. 51—209)

This invention relates to a further development of flexible grinding tools of hollow cylindrical shape with heat-resistant bond composed of thermosetting synthetic resin.

Grinding tools have already been proposed which possess the geometrical shape of hollow cylinders with parallel side walls. These abrasive cylinders can be of different diameters and arranged one within the other concentrically on a carrier disc. Grinding tools constructed in this manner must run at a very high working speed because the wear when working solid and hard materials increases as the working speed decreases. An increase in the working speed beyond 90 metres per second is limited by the strength of the abrasive tubes wound from fabric webs. The wall thickness of these tubes, and especially the flange height, that is the effective abrasion height of the abrasive body forming the multiple-cup disc or wheel, must not exceed a certain measurement because, by increasing the effort arm on which the centrifugal forces act, the speed of rotation at which the abrasive ring will burst is reduced. The multiple-step grinding rings (multiple cup discs), owing to these limits, only enable relatively small quantities of material to be ground down completely and are primarily suitable for lighter work, for example for sharpening tools, grinding work with small machining allowance, and so forth.

In order to remove greater quantities of chips, for example when grinding the heads of railway rails, the surface of tubes and the like, it has also been proposed to use multi-step segments which have a relatively large curvature radius. To avoid undue unbalance, the individual segment shells must be pressed with relatively great precision. When the segments have been placed in a grinding wheel this must be balanced.

In order to remove the above-mentioned limits to the employment of the abrasive bodies which have already been proposed, it is proposed according to the present invention to use, instead of the multi-step grinding rings of relatively large diameter and the multi-step segment bodies, tubes preferably wound from fabric webs and of small diameter with a heat-resistant bond composed of thermosetting synthetic resin, the length of these tubes being many times greater than their outer diameter, the tubes being arranged adjustable in longitudinal direction, axially, radially or at an incline to the axis of rotation of a metal carrier (grinding wheel).

To work surfaces of relatively large area, for example the surface of metal sheets, grinding rolls can be employed. Abrasive tube sections are slipped on to bolts radially fixed in rings by pinning, by internal clamping devices or the like. By assembling such rings set with four to six abrasive tube sections, grinding rolls can be formed the width of which is variable, so that they can be adapted to the surface to be worked. As the width of these rings corresponds to the internal diameter of the abrasive tube sections, the paths produced during the grinding operation overlap so that no steps are formed on the surface of the workpiece. It is evident that the

2

whole grinding roll may be profiled by suitably shaping the individual abrasive tube sections.

For internally working, for example tubes, the abrasive tube sections can also be fitted in levers which spread under the action of centrifugal force and are hingedly connected with a shaft rotating at a high speed. The internal working of bores is naturally also possible with grinding rolls, the abrasive tube sections of which are preferably radially adjustable and readjustable, for example by the axial displacement of a mandrel within the roll.

The cross-sectional shape of the abrasive tubes has a corresponding influence on the grinding output. Contrary to face and wall grinding wheels, the abrasive tubes according to the invention can attain considerably greater grinding performances, due on the one hand to the existing bore, that is the existing free space and the thin wall thickness which does not prevent the leading off of the chips produced by the grinding operation, and on the other hand to the high working speed possible when using web-wound and compressed abrasive tubes. The cross-sections may be of any shape, for example circular, rectangular, hexagonal and so forth; they may also be in the form of ring sections which, when fitted together, produce a circular path. If a plurality of such circular paths were to be arranged concentrically to each other, the abrasive tubes having the cross-section of one ring section are provided with spacers. The cross-section of the tubes should be so dimensioned that a sufficient quantity of abrasive material with corresponding cutting capacity can be accommodated.

With a view to producing greater abrasive tube volume increasing the chip removing capacity, the free cross-sectional area of grinding tubes of any shape can be additionally reduced by introducing more abrasive bodies. Care must, however, be taken that there is sufficient free space for leading off the larger quantities of chips produced. The additional abrasive bodies introduced can be rigidly connected with the outer abrasive tubes by welding, sticking or the like.

By means of wear-proof spacers, adjustable in relation to the surface engaged by the grinding tools, it is possible, as these spacers are in continual contact with the surface of the workpiece, for the end face of the tubular grinding tool to bear only lightly in relation to the unbroken, flat or concave surface, for example the inner wall of a tube, with the result that the wear of the abrasive tubes is considerably reduced. The wear-proof spacers can serve at the same time as means for measuring during the grinding operation.

Several embodiments of the invention are illustrated by way of example in the accompanying drawings, in which:

Figure 1 is a cross-sectional view through a tubular grinding tool having embedded therein abrasive bodies.

Figure 2 is a diagrammatic view showing how two concentric grinding elements are secured together.

Figure 3 is a similar view showing a modification.

Figure 4 is a similar view illustrating a further modification.

Figure 5 is a similar view with parts in cross-section illustrating a still further modification.

Figure 6 is a view similar to Figure 2 showing a still further modification.

Figs. 7 and 8 are top plan and cross-sectional (diagrammatic) views respectively of a grinding device in which tubular abrasive bodies are fitted in a carrier parallel to the axis of rotation thereof;

Fig. 9 is a cross-section through the grinding device (diagrammatically illustrated), in which tubular abrasive body sections are inserted in a carrier at an incline to its axis of rotation;

Fig. 10 is a top plan view of a grinding device in which the pitch circle of the tubular abrasive tools can be varied by means of flat spirals;

Fig. 11 shows a cross-section through a grinding device, in which the tubular abrasive tool sections are arranged radially and fixed on pins of a disc-shaped carrier;

Fig. 12 is a side elevation of a grinding device for working the interior of tubes and in which the abrasive tube sections are mounted on levers pivotally connected with a rotary shaft and press the abrasive tube sections against the tube wall under the action of centrifugal force;

Fig. 13 shows in longitudinal section a grinding device in which the adjustable abrasive tubes of considerable length are fitted in a driven horizontal cylinder supported at both ends;

Fig. 14 is a cross-section through the grinding device illustrated in Fig. 13 (without cross-piece according to Fig. 16);

Fig. 15 shows a support serving as rest for the abrasive tubes and rigidly connected to the outer jacket of the grinding device according to Fig. 13;

Fig. 16 shows in elevation a cross-piece for simultaneously shifting in longitudinal direction by means of screw-spindles a group of abrasive tubes screwed to the cross-piece;

Fig. 17 shows the cross-member according to Fig. 16 in top plan view;

Fig. 23 is a side elevation, partly in section, of a grinding device with vertical arrangement of the grinding spindle with relatively short abrasive tubes fitted parallel to the axis of rotation, which can be easily readjusted and fixed by hand and which can in addition take fillings of abrasive material;

Fig. 24 is a front elevation, partly in section, of a grinding roll which is composed of annular carriers with radially inserted abrasive tube sections forming a grinding roll set; and

Fig. 25 is a side elevation, partly in section, of the grinding roll illustrated in Fig. 24.

In Figs. 1 to 6 and 18 to 22 the cross-sections through the tubular grinding tools, which are preferably composed of wound fabric webs bound with synthetic resin, between the metallic or non-metallic layers of which hard material grains 2 are embedded under strong pressure, are designated by 1. Only in Fig. 1 are the wound fabric webs also shown in section. As illustrated in Figs. 2 and 6, elongated abrasive bodies 3 can be additionally introduced into the tubular abrasive bodies 1 and may also be composed of wound, highly compressed fabric webs impregnated with abrasive grit. If the wound tubes are compressed by four radially arranged rams, lugs are also formed as shown in Fig. 2, which lugs enable the abrasive body 3, which is also of tubular shape, to be fitted in the grinding tube 1 in such a manner that gaps or spaces remain and serve for removing chips and feeding loose grit. The cross-section of the additionally inserted elongated abrasive bodies 3 may, as shown in Figs. 3, 4 and 6, also be of rectangular, star or even triangular shape respectively. Any cross-sectional shape can be chosen in order to increase the effective volume of the grinding tube 1 by means of such insertions 3 carrying additional abrasive material.

According to Fig. 5 additional tubes 3' to 3''' of smaller diameter can be inserted in the grinding tube 1 and also serve for enlarging the effective volume or also for introducing loose abrasive grit. The hatching in the case of 3''' in Fig. 5 is intended to indicate that these insertions 3 can also be solid, that is entirely impregnated with bonded abrasive grain. In any case it is necessary to retain free spaces 4 for leading off the grinding chips produced. As regards the possible cross-sectional shapes, Fig. 18 shows a tubular grinding body 1 of hexagonal shape. This shape allows the space serving for accommodating the abrasive bodies in a carrier, to be filled in such a manner that the abrasive bodies are side by side. When the tubular grinding body is of rectangular cross-sectional shape as shown in Fig. 19 the fabric is first wound with interposed abrasive grit onto a mandrel corresponding to the free cross-sectional, rectangular shape shown in Fig. 19. The wound laps must then be subsequently compressed by rams which so act that the longitudinal sides of the rectangle are considerably thickened. By this means a particularly high resistance to wear and a firm embedding of the abrasive particles are obtained in these zones. The above-mentioned compressing operation can be attained in that the sides 48 of the rectangle producing the cross-connection, have not the same high degree of compactness as the other sides, so that they wear away more quickly during the grinding operation with the result that the longitudinal sides are exposed. Similar conditions can be produced in the case of the tubular grinding bodies having a cross-section in the shape of a circular ring section as shown in Figs. 20 to 22. These grinding tubes having a cross-sectional shape of a ring section (see Fig. 20) can be arranged side by side on a carrier disc so that grinding paths with the same curvature radius are produced. Also in this instance, when a compressing tool as shown in Fig. 21 is used, greater wear will occur during the grinding operation in the regions of the connecting webs or arms 48, so that the surface of the arms 48 will always bear slightly below the grinding surface of the slightly curved longitudinal sides representing the actual grinding path.

The compression can be effected in the manner shown in Fig. 21 by guiding the rams 45 and 46 in the pressing tool 47 so that they compress the laps wound on a curved mandrel. At the same time the greatest pressure is not transmitted between the two curved longitudinal sides so that the abovementioned wearing effect takes place. If the lower die or ram 46 is shaped as shown in Fig. 21, the spacer arms 44 are formed at the same time during the pressing operation and these arms, according to Fig. 22, enable a plurality of grinding bodies with cross-sections of circular segmental shape to be arranged one above the other, with the result that uniform spacing of the curved paths can be maintained. According to Fig. 22, recesses are provided in the rotary carrier 5 for receiving a plurality of superposed tubular abrasive bodies with circular ring-section-shaped cross-section which are held in these recesses in the carrier 5 by the exertion of pressure (50). Furthermore, the abovedescribed tubular grinding bodies 1 and 1' can also be interconnected by plastic plates or metal plates 49.

The tubular grinding bodies 1 can be inserted in the carrier 5 as illustrated in Figs. 7 and 8. In this case the central axes of 1 lie in the same pitch circle. Arrangements can, however, likewise be provided wherein the central axes of the tubes, here designated by 8, are located on a smaller or larger pitch circle. The carrier body 5 is provided with a bore 7 so that it can be slipped on to grinding spindles. The grinding plane is designated by 22 in Fig. 8. The tubular grinding bodies 1 can also be set at an angle to the axis of rotation of the carrier 5, as shown in Fig. 9. It is possible with this arrangement to surface-grind the walls of bores, for example of tubes. Instead of the four grinding tubes shown in this

figure, it is evident that a greater number of grinding tubes can be fitted in the carrier 5. If the holders 10 for the tubular grinding bodies 1, shown in Fig. 10, are slideable in a radial guide 9, the diameter of the pitch circle of the grinding tubes 1 can be varied by the radial displacement of these grinding tubes by means of flat spirals 13 worked in a ring 12 rotatable in relation to the carrier 5. The holders 10 are connected with the flat spirals 13 through the intermediary of intermediate members 11. If the tubular grinding bodies are of relatively great length, two rings 12 and two flat spirals 13 are provided in the carrier 5, which for this purpose is made of cylindrical shape, so that the holders provided for the front and rear ends of the tubes, as well as the grinding tubes fitted therein, carry out a radial parallel displacement in relation to the axis of rotation of the carrier 5.

In addition to the axially parallel and inclined arrangements of the tubular grinding bodies 1 according to Figs. 7 to 9, grinding tube sections may be employed arranged as shown in Fig. 11, so that they can be fitted on pins 14 connected to the carrier ring 5 by means of a screw-threaded extension 15. The grinding tube sections 1 can be fixed on the pins 14 by means of transverse pins, by known internal clamping devices or by providing the pin 14 and also the bore of the grinding tube sections 1 with screw threads. The carrier ring 5 has a bore 7 and rotates about the central axis shown in Fig. 11. By profiling the guiding tube sections 1 fitted on the pins 15 it is possible to surface-grind workpieces having a certain, for example, curved profile.

If bores, for example the inner wall 21 of a cylinder 20, are to be ground, the grinding tube sections 1 may, according to Fig. 12, be mounted on two or more one-armed levers 18 and 19, which are connected by a hinge 17 with the rotary driving shaft 16 running at a high speed, so that, during the rotation, the grinding tube sections 1 are pressed by the centrifugal effect in the direction of the arrows against the tube wall. During the grinding of the wall 21 of a tube having a diameter D, the whole grinding wheel must carry out a feed movement in the direction of the arrow S. As herein-after set forth in the description of Figs. 24 and 25, the internal grinding of tubes can also be carried out with grinding rolls which can likewise be varied as regards their effective diameter.

In Figs. 13 to 17 a construction for grinding the outer wall of tubes is shown by way of example as an embodiment of the invention. Seeing that in this case large quantities of material have to be removed, it is necessary to employ tubular grinding bodies of great length. These tubes 1 having an initial length of 1 metre and more, are placed in a cylindrical grinding construction (Fig. 13) which consists substantially of the following parts: The outer casing 23 made from very resistant steel, the carrier tube 27, the four spacers 28 for establishing a firm connection between 23 and 27, covers 25 and 26 fitted in the ends, the shaft 35 centrally arranged in the construction and which does not participate in the rotation, the roller bearings 34, the pillow blocks 36 which are bolted to the sliding carriage 39 and the supports 24 rigidly connected with the outer casing 23 and serving as bearing surface for the grinding tubes 1 acted upon by centrifugal force (see also Fig. 15).

The tubular grinding bodies 1 arranged in groups of three (in Figs. 14 to 17), are secured to a cross-piece 42 by means of screws 43, which cross-piece is guided on the carrier tube 27, the spacers 28 and the profile of the support 24 facing the axis of rotation (see Figs. 13 and 16).

According to Fig. 17, the cylindrical members 29 are inserted in the grinding tubes 1 so that they can be secured by screwing. Each four groups of grinding bodies are fitted in the grinding construction according to Figs.

13 and 14. With the aid of screw spindles 30, carrying pins 31 at both ends, and of an epicyclic gear 32/33, the tubular grinding bodies 1 can, on being simultaneously and uniformly turned in the construction, be shifted in axial direction and so adjusted that a small portion of the grinding bodies 1 projects from the cover 25 facing the tube 38 to be ground. For grinding the cylindrical outer wall or jacket of tubes the working surfaces 22 of the tubular grinding bodies 1 are so profiled that a larger surface of the bodies 1 contacts the outer wall or jacket of the tube 38 to be ground. As continuous wear takes place during the grinding operation, the tubular bodies must be periodically or continuously readjusted by means of the constructional elements 30, 32, 33 and 42. In the case of periodic displacement of the bodies 1, the feeding movement must be effected by the carriage 39 carrying the construction and which can be coupled with a precision spindle.

The amount of adjustment of the grinding construction according to Fig. 13 in relation to the horizontal central axis of the tube 38 to be surface ground, must be effected in such a manner that the greatest effective diameter of the tubular grinding body 1 is located in the middle. The grinding construction can be driven by means of a belt 37. The speed must be such that the grinding tools 1 operate at an average working speed of 90 metres per second.

The grinding device 5 with vertically arranged grinding spindle 52 illustrated in Fig. 23, has a relatively large number of axially parallel bores 63 of the same pitch circle diameter, in which bores the tubular grinding bodies 1 are inserted by hand. The grinding spindle 53 is held, for example, in the arm 62 of the grinding machine by clamping. The tubes 1 inserted by hand are allowed to rest on the surface 22 to be ground when the machine is at a standstill and are then clamped, for example, by means of hydraulically operating pressure means built up in the following manner:

A piston 57 arranged radially in front of each grinding tool 1 can be moved by pressure fluid which is fed via the passages 58, 60 and 61. The annular recess 58 turned in the grinding device 5 is closed by means of a screw ring 59. The centrifugal forces occurring at the speed of rotation necessary for the grinding device 5 also produce an amply tight seating of the tubes 1 inserted by hand. The surfaces of the bore 63 against which the grinding tools 1 are pressed by centrifugal effect are preferably provided with transverse grooves, screw threads, roughened surfaces and the like, and similarly a portion of the outer wall of the tubular grinding tools. With this type of holding means for the grinding tools 1 a slight stress, for example spring pressure, is sufficient once the tools have been inserted in the carrier 5. For fixing the grinding tubes 1 in the grinding device 5 any of the known clamping arrangements can be employed, including those using plastic agents, such as neoprene.

The grinding device is mounted on a conical pin 54 formed on the grinding spindle 53 and there held by means of screw 55 with interposed washer 56.

The spaces 63 for receiving the tubular grinding tools 1 may be of any desired cross-sectional shape, for example also for taking those having the cross-sectional shape of circular ring segments or sections such as those shown in Figs. 20 and 22.

For the economical chip removal of large volumes of material, for example when surface grinding metal sheets, as shown on the right-hand side of Fig. 23, provided it is a question of unbroken surfaces from which the grinding device is not raised during the grinding operation, cartridges enclosed in thin, easily worn away casings 69 and filled with accurately dosed quantities of loose abrasive grit 68 are inserted in the tubular grinding bodies and pressed under elastic pressure against the surface 22 to be ground, for example by means of an air cushion

or bag 70 which can be supported by a disc 71 fixed by a cross-pin 67. A valve 72 ensures that a certain pressure is maintained in the bag 70.

At the beginning of the grinding operation, the portion of the thin casing of the cartridge facing the surface of the workpiece will naturally be rubbed away, so that the abrasive grit 69 is exposed and becomes effective. These abrasive grit cartridges may also be of any desired cross-sectional shape, so that they can likewise be introduced into the free cross-sectional spaces in the grinding tubes 1, as shown, for example, in Fig. 20. The abrasive grit of the cartridges may, as already mentioned in the introduction to the specification, be held in light bond by various means to enable the grinding device to be, if necessary, lifted off the surface of the workpiece during the grinding operation.

Whereas the grinding device shown in Fig. 11 has a carrier ring 5 which is wider than the largest diameter of the grinding tube sections 1 slipped on to the plugs or pins 14, the carrier rings 5 of the construction illustrated in Figs. 24 and 25 are only of a width corresponding to the internal diameter of the grinding tube sections 1. Also in this case these latter are slipped on to the pins or plugs 14 which are screwed into the carrier ring 5 by means of screw-threaded extensions 15 or are made integral therewith. The bodies 1 may be fixed on the pins 14 by cross-pins 66, by an internal clamping arrangement not shown on the drawing, or by screw threads which would have to be provided on the pins 14 and in the bores of the bodies 1. Owing to the narrow width of the rings 5 it is possible to assemble and unite the individual grinding devices, composed of the ring 5 and the plugs or pins 14 connected therewith, with the grinding tube sections 1 slipped thereon, to form sets (5', 5", 5'', 5''' and so forth) by means of a centrally arranged shaft 64 and a ring nut 65, so that a grinding roll is produced, the width of which can be adapted to the surface of the workpiece to be ground. The grinding tube sections of the carrier ring 5" (Fig. 24) are, as indicated by the references 51 and 52, displaced, for example, through an angle of 30° in relation to the position of the grinding ring sections 1', 1", 1''' and 1'''' (the last position is not shown in the drawing) of the carrier ring 5, so that uniformity is ensured during the grinding operations by means of the roll and also, by the staggered arrangement, the power consumption shows no unnecessary fluctuation during the grinding operation. The narrow width of the carrier rings 5 allows an overlapping of the grinding paths so that no steps or irregularities are produced on the surface worked.

By the application of suitable measures, for example, by using a mandrel tapering in the axial direction of the grinding roll or a conical sleeve, it is possible to change the effective external diameter of the grinding roll by radially shifting the plugs or pins 14, so that the diameter of the roll can be adapted to the diameter of bores, for example of tubes. Readjustment as the grinding tube sections 1 of the grinding roll wear down is also rendered possible by this means.

The abrasive grit cartridges mentioned in the description of Fig. 5 can also be inserted in the free apertures in the grinding tube sections 1 both of the grinding device according to Figs. 24 and 25 and also of that shown in Fig. 12, seeing that unbroken surfaces also come into

60 65

question in the case of internal grinding of the tubes. Thus new methods of grinding the inner wall of tubes are offered by the invention.

Finally it is also pointed out that the bonding material of the tubular grinding bodies can be the same as that of the grinding wheels which are already known. As the end of the tube directed towards the surface to be ground only extends a small amount from the carrier and the tube bears on practically its entire length within the carrier, the centrifugal forces produced at the high speeds of rotation are taken up by the carrier itself, so that, in addition to the very tightly wound tubes with plastic bond, tubes can also be used which are produced, for example, by saturating with thermosetting synthetic substances into which the abrasive particles can also be introduced in the form of a tube, if desired adding a few laps of very strong steel wire fabric, whereupon the bond is established by pressure saturation.

The fact that the centrifugal forces which occur are absorbed by the carrier also enables the use of the known vitrified bonds even in the case of tubular grinding bodies of relatively great length. Also in this case, all the cross-sectional shapes mentioned in the preceding specification can be employed. A combination of different kinds of bonds is likewise possible so that, for example for reasons of the total bending strength, the outer tube 1 according to Fig. 5 can be composed of wound fabric webs bonded with synthetic resin, whereas the inserted tubular grinding bodies 3 may have a vitrified bond.

30 I claim:

1. Multi-path grinding elements comprising a plurality of tubular, thin-walled grinding elements formed from synthetic material saturated, wound and heavily compressed fabric webs with abrasives embedded therein, said grinding elements being arranged concentrically to one another, and said grinding elements contacting each other at spaced places and being fixedly connected to each other at said places, and said grinding elements having a relatively wide interval between them for the removal of grinding chips.

2. Grinding elements as claimed in claim 1 wherein two tubular grinding elements are concentrically arranged to each other and ribs are pressed upon the interior grinding element by which said two grinding elements are connected with each other.

3. Grinding elements as claimed in claim 1 wherein a plurality of smaller grinding elements are arranged within a larger grinding element.

4. Grinding elements as claimed in claim 3 wherein said smaller grinding elements are solid.
